UNITED STATES PATENT OFFICE.

JOHN S. GOLDBERG, OF CHICAGO, ILLINOIS, ASSIGNOR TO STROMBERG MOTOR DEVICES COMPANY, OF CHICAGO, ILLINOIS.

CARBURETER.

1,128,773.

Specification of Letters Patent.

Patented Feb. 16, 1915.

Original application filed December 17, 1910, Serial No. 597,757. Divided and this application filed March 19, 1914. Serial No. 825,756.

To all whom it may concern:

Be it known that I, JOHN S. GOLDBERG, a citizen of the United States, residing at Chicago, in the county of Cook and State of Illinois, have invented a certain new and useful Improvement in Carbureters, of which the following is a full, clear, concise, and exact description, reference being had to the accompanying drawings, forming a 10 part of this specification.

My invention relates to carbureters, such as are employed in association with automobile engines, and contemplates means for properly controlling the richness of the combustible mixture produced thereby.

The present invention has to do primarily with that type of carbureter in which a fuel inlet is associated with an open main air inlet and in which an auxiliary air inlet is 20 provided, this auxiliary inlet being normally closed but being so controlled that it automatically is opened when a sufficient degree of suction has been produced in the carbureting chamber.

It is well-known that, unless some means is provided to compensate therefor, it is the tendency for a mixture formed by a single fuel inlet in an air passage to become too rich as the suction increases, and the auxiliary air valve which responds on the greater suctions is provided, according to 30 my invention, in order to properly compensate for this undesirable increase in richness of mixture. In order, however, that the proper mixture may always be maintained and in order also that the nicety of adjustment may be enlarged, I associate with the auxiliary air inlet an auxiliary fuel inlet which is arranged to be subject to the aspira- 35

40 rating effect of the air entering this auxiliary air inlet. Thus, I have a main fuel nozzle, subject practically exclusively to the aspirating effect of the air entering through the main air inlet, and a secondary nozzle, subject practically exclusively to the aspirating effect of the air entering the auxiliary air inlet, which is controlled by a valve subject to the pressure below the throttle. By this means, I am enabled to se- 45 cure a very fine control of the mixture richness, since the diluting effect of the auxiliary air valve is properly graded by the effect of the air entering by that valve on the fuel inlet especially provided for it.

Since both fuel nozzles and both air inlets 55 are subject to the pressure on the same side of the throttle, the adjustments that I provide may be relatively set so as to secure the proper richness of the mixture at all suc- 60 tions and, with this end in view, I have pro- vided the various parts which will be re- ferred to later.

In Patent No. 1,099,293, issued June 9, 1914 to Harry C. Tillotson and myself as joint inventors, there is set forth and 65 claimed an arrangement wherein a secondary fuel inlet is provided and wherein this secondary fuel inlet is permanently open to the carbureting chamber below the throttle. In that application, the height of the nozzle is 70 relied upon to effect the necessary delay in the response of the secondary fuel nozzle, while in the present application, the sec- 75 ondary fuel nozzle is controlled by a valve which coöperates with the valve for the aux- iliary air inlet so that the fuel nozzle is opened at the inception of the opening movement of the air valve or at a definite point after the air valve has opened.

The present application is divisional from 80 the application which resulted in my Patent No. 1,119,078, dated Dec. 1, 1914 wherein the claims relate to the construction of the fuel nozzle.

My invention is embodied in the structure 85 illustrated in the accompanying drawings, in which—

Figure 1 is a vertical longitudinal sec- 90 tional view of my carbureter; and Fig. 2 is a plan view thereof. Fig. 3 is a detail view which will be referred to.

Extending from the top of the body part 95 of the casing 1, at the side opposite the shelf 2, is the casing 3, which forms an auxiliary air inlet chamber 4 and serves to sup- port the various parts of the secondary au- 100 tomatic valve mechanism which will be de- scribed. The main body part of the casing comprises the annular base 5 from which the outer cylindrical shell 6 extends upwardly, this shell being supplemented upon the inside by an inner shell 7, as clearly shown in the drawings. The space between the shells 6 and 7 forms a heating jacket through which hot water may be circulated.

Across the base 5 is the bridge section 14 which supports a sleeve 15 extending down- 105 wardly therefrom in axial relation with the

base 5 and the shell 7. The bridge 14 also supports the upwardly extending sleeve 16, which is disposed in axial alinement with the sleeve 15. The sleeve 16 is provided with an axial threaded opening in which is threaded a nozzle piece 17, this nozzle piece having the nozzle opening 18 and the central bore 19 which thus communicates with the inside of the sleeve and thereby connects with the horizontal passageway 20 which leads to the shelf 2, as will hereinafter be described. The lower end of the sleeve 15 is internally screw-threaded for the reception of a plug 21, this plug having a central bore for the reception of the stem 22 of a needle valve 23. This stem 22, at its lower end, passes into a pocket 24 in the plug, which pocket is provided with screw-threads for the reception of the screw-threaded adjusting piece 25, which is in rigid relation with the stem 22. As will be apparent from the drawings, this adjusting piece 25 is adapted for manual manipulation, and it is clear that turning the adjusting piece one way or the other will result in the upward or downward movement of the stem 22 and, consequently, of the valve part 23. This valve part 23 is in the form of a needle valve and is provided with the axial passage 26 and the cross passages 27, 27, connecting therewith. When the adjusting piece 25 is turned so as to lower the needle valve, the head of the valve 23 will be separated from the nozzle piece 17 so as to leave an annular passageway, the nozzle piece, in this instance, having a tapered seat for the reception of the tapered valve head. The resulting annular passageway acts in parallel with the passageway 26, and it will appear that if suction is applied at the nozzle opening 18, fuel may be drawn through the passageway 20, up through the sleeve, through the passageway 26 alone or in conjunction with the annular passageway, through the bore 19 and through the nozzle opening 18. Since these are fuel passageways, the plug 21 is stuffed, as indicated at 28, the stuffing box being completed by means of the collar 29, which has threaded engagement with the pocket in the plug. The arrangement above described, this double nozzle arrangement, is for the purpose of adjusting the fuel spray.

The nozzle opening 18 is the maximum nozzle opening and the passageway 26 is the minimum nozzle opening. In other words, the nozzle opening 18 is larger than the passageway 26, the former being the desired maximum limit and the latter being the desired minimum limit. It will appear that when the valve head 23 is screwed up tight into the nozzle piece 17, the passageway 26 will determine the flow of the fuel. And since this passageway determines the flow alone, it will appear that when the parts

are in this position the minimum flow of fuel will take place. When it is desired to increase the amount of fuel passing from the nozzle, the adjusting piece 25 is turned in the proper direction so as to separate the valve head 23 from the seat in the nozzle piece 17 so as to supplement the passageway 26 by the annular passage. Thus, as the adjusting piece 25 is turned so as to lower the conical head 23 away from its conical seat, the annular passageway gradually becomes larger and the flow of fuel may be increased until the combined effective areas of the annular passageway and the passageway 26 are equal to the cross-sectional area of the nozzle opening 18. After this, the continued manipulation of the adjusting piece 25 in that direction will have no effect, since the nozzle opening 18 alone will determine the flow of fuel. This will be the maximum flow. Thus, even though the adjusting piece 25 be screwed down to its limit, no less than the desired minimum flow of fuel takes place. Similarly, if the adjusting piece 25 is turned in the opposite direction to such an extent as to move the head 23 a considerable distance from the nozzle piece 17, no more than the maximum flow of fuel will take place, and the entire arrangement is, therefore, guarded against improper manipulation by an inexperienced person.

The lower section of the shell 7 is of the same inner diameter as that of the annular base portion 5, while the intermediate zone 30 of the shell 7 converges conically upward so that the imaginary apex of the upper surface of said zone will coincide with the upper end of the nozzle piece 17. The upper section or zone 31 of the shell 7 diverges toward and meets the upper end of the outer shell 6. We thus have a more or less central passageway through the carburetor, the lower zone of this passageway being cylindrical, the intermediary zone 110 conically convergent and the upper zone 110 divergent, the nozzle end lying in the apex of the intermediary conical zone. The lower end of the passageway, as will be described later, during the running of the engine, is open to the atmosphere, and air can therefore enter and flow upwardly through the passageway, this air being deflected by the conical walls of the intermediary zone and its energy directed across the outlet of the nozzle to extract oil therefrom; and the diverging zone will cause the air and oil to become thoroughly mixed to form a suitable mixture with which the engine is to be supplied.

A socket member 32 is slipped over the downwardly extending sleeve 15 and is held in place against the bottom of the sleeve 15 by means of the nut portion 33 of the plug 21, as clearly illustrated in Fig. 1. The

socket member 32 is provided with a prong 34 which engages a lug 35 extending from the base portion 5 of the carburetor casing proper. This engagement prevents the cup 5 and the parts carried thereby, as will be described, from turning when all the parts are properly set in place. The major portion of the socket member 32 is in the form of a sleeve surrounding the sleeve 15 and upon this outer sleeve a collar 36 is loosely mounted. This collar is of such diameter that it may close the main inlet passageway of the carburetor, but it is normally held in its open position, against a suitable shoulder 37 on the socket member 32, by means of a helical spring 38 resting in an annular groove 39 in the collar and engaging the under side of the bridge 14, all as indicated in Figs. 1 and 2. The socket member 32 is 10 suitably enlarged, as shown, to provide a bearing for a pin 40 which extends at right angles to the axis of the sleeves. Upon this pin one or more cams 41, 41 are secured, these cams engaging the under side of the collar 29, as indicated in the drawings so as 15 to raise the collar to restrict the main air inlet temporarily. This arrangement is clearly illustrated in Fig. 3.

The shelf 2 supports the cylindrical glass shell 43, covered by a cap 44, the base, the shell and the cap forming an oil receptacle. The shelf 2, which, except for its connection with the main body of the carburetor, is circular, has a central opening which is 20 surrounded by a flange 45 and a fuel inlet frame 46 is held tightly against this flange by means of a coupling 47. The shelf 2 supports a valve disk 48, the central portion of which is in the form of a boss extending down through the central openings, this arrangement being held tightly in place by means of a nut 49. The valve disk 48 has the central passageway 50 which thus connects with the source of fuel, this central 25 passageway, as shown in the drawings, being countersunk to form a suitable beveled valve seat. Extending upwardly from the valve disk 45, concentric with the passageway 50, is a sleeve 51, which is screw-threaded at the top so that it may engage by that means in a central opening in the cover 44 and so hold the cover in place. A stem 52 is disposed in this sleeve, this stem being provided at the bottom thereof with a pocket 30 in which a valve spindle 53 is hung upon a pin 54. The valve point 55 is adapted to engage the seat in the valve disk 48 so as to control the passageway 50. The lower end of the sleeve 51 has the diametrically opposite slots 56 and 57 across which pins 58, 58 are disposed. Upon these pins the foot-shaped levers 59, 59 are mounted, the toes 60, 60 of these levers being arranged to engage the lower end of the stem 52, as 35 clearly illustrated in Fig. 1. An annular

float 61 encircles the sleeve 51 and is loosely disposed relatively thereto so that it may rise and fall with the level of the oil in the float chamber, as will be pointed out.

The main portions of the levers 59, 59 70 engage the under side of this float and it is clear that the weight of this float will cause the main portions of these levers to move downwardly while the toes thereof will move upwardly and raise the stem 52 75 against the tension of the helical spring 61', which is disposed inside the sleeve 51 around the stem 52 between a shoulder 62 on the stem and the inside of a cap 63 which screws down over the outside of the sleeve. 80 It will be apparent that, since the oil enters through the passageway 50, the float 61 will be gradually raised and, because of such operation, the spring 61' will force the valve head 55 down to close the passageway 50 to 85 a greater or less extent. As the oil in the float chamber, the passageway 20, and associated passageways, becomes depleted, the float 61 will gradually lower and allow more oil to enter through the passageway 50 and 90 thus a constant supply of oil is maintained. It is apparent that the tension of the spring 61' may be adjusted by screwing the cap 63 down upon the stem 51 to a greater or less extent, and in order to lock the cap 63 in 95 any adjusted position, I provide a series of vertical grooves 64, 64 therein. Associating with these grooves is a plunger 65 which rides in a pocket in a screw 66 suitably mounted in a boss 67 on the cover 44, the 100 helical spring 68 being provided to maintain the plunger 65 in engagement with one of the grooves 64. The plunger 65 has a rounded head so that the cap 63 may be turned without any particular unlocking, but it is clear that the plunger will hold the cap in position against being jarred out of place or against any accidental movement. The stem 52 passes out beyond the cap 63 through a bolt 69 therein, and the stem has secured in its upper end a secondary cap 70 which extends over the end of the primary cap 63 so as to secure a dust-proof arrangement. If particles carried in the oil should become clogged in the valve seat at the passageway 50 and should thus interfere with the operation of the valve and the parts associated therewith, the cap 70 may be grasped manually and raised against the tension of the helical spring 61' 115 120 so as to work the valve head 55 and thus clean the arrangement at that point.

The frame section 71 above the walls 6 and 7 forms a mixing compartment or chamber 72, which communicates with the upper end of the main central passageway which has hereinbefore been described. The upper end of the frame 71 has a flange 73 by means of which connection may be made with the engine to be supplied. A shaft 74 130

extends diametrically through the frame 71 and carries a disk valve 73 operable by means of a suitable lever 76 also secured upon the shaft. The chamber 72 also communicates with the auxiliary valve chamber 4 by means of a passageway 77. On the top of the casing 3 is supported the valve frame 78, which is constructed in the form of a spider and has the passageways 79, 79, 10 through which the valve chamber 80 may communicate directly with the atmosphere. The lower edge of the valve frame is beveled to form an annular valve seat 81, with which a disk valve 82 co-operates. The 15 valve disk hub 83 is secured to a valve stem 84, which passes axially through the hub 85 supported from the valve frame 78 by means of the radial members 86. The bottom of the casing 3 has an opening in axial alignment with the stem 84, which opening is surrounded by a sleeve 87 which extends a considerable distance downwardly. This sleeve is internally screw-threaded for the reception of the plug 88 which has an axial opening in which a thimble 89 is disposed, this thimble being provided with an annular shoulder 90, which rests upon the top of the plug, as clearly illustrated in Fig. 1. The axial pocket in the thimble 89 receives 20 the lower end of the stem 84. The plug 86 is surrounded by the sleeve 91 which is held against the annular shoulder 92 on the plug by means of a pin 93, this cup extending upwardly, as shown in Fig. 1, to inclose the 25 lower end of the sleeve 87. A helical spring 95 surrounds the stem 84 and is disposed between the under side of the valve member 82 and the shoulder 96 on the thimble 89.

It will appear that when the thimble 89 30 rests upon the top of the plug 88, the tension of the spring 95 can be adjusted by turning the sleeve 91 in one direction or the other. It is clear that turning the sleeve will result in corresponding movement of 35 the plug 88, and it is clear that such movement of the plug will move it upwardly or downwardly to change the tension of the spring 95 and its effect upon the valve piece 82. The valve is guided in its movement by 40 means of a pin 97 which passes through an opening 98 in one of the cross-pieces 86. The sleeve 91 and the associated parts are the elements that are provided for permanent adjustment of the spring 95 so that 45 the valve 82 may respond to the suction of the engine at the proper time. In order to hold the sleeve 91 in any adjusted position, this sleeve is provided with a plurality of 50 grooves 99 in the periphery thereof, these 55 grooves being parallel to the axis and being adapted for the reception of a plunger 100 which operates in a pocket in a screw 101 which is mounted in a lug 102 extending from the casing 3. A spiral spring 103 is disposed in the pocket, as clearly illustrated 60

in Fig. 1, to hold the plunger 100 in engagement with any one of the grooves 99. The head of the plunger 100 is rounded so that unlocking is unnecessary and it is merely required to turn the sleeve 91 against this drag until the succeeding groove is reached. This is sufficient to hold the sleeve against movement by reason of jars or accidental manipulation. As has been described, the primary nozzle and air inlet arrangement 75 are sufficient to meet the demands of the engine only to a certain extent.

When the demand reaches a certain point the suction is sufficient to open the valve 82 against the tension of the spring 95 and, 80 as has just been pointed out, the spring 95 is adjusted so that the response of the valve 82 may take place at the proper time. In order that the tension of the valve 95 may be varied while the machine is running and 85 when it is not practical to operate the permanent adjusting means which has just been described, I provide means for temporarily raising the thimble 89 upon which the lower end of the spring rests. This arrangement is in the way of a bell-crank lever 104 which is pivoted at 105 in a lug 106 extending from a yoke 107 pivotally mounted upon the sleeve 87. The rounded lower end of the thimble 89 is engaged by 90 the arm 108 of the bell crank lever 104 and the other arm 109 is connected at 110 with suitable connecting mechanism which leads to operating means within the reach and control of the operator. It is seen, referring 95 to Fig. 1, that when the bell-crank lever 104 is turned in a clockwise direction, the other arm 108 thereof will move upwardly to transmit the corresponding movement to the thimble 89. This will compress the 100 spring 95 and will increase the tension thereon and it is evident that while the bell-crank lever 104 is thrown over in this position, the response of the valve 82 to the suction is retarded. Pivotaly supported to 105 the extension 111 from the frame 78 is the lever 112 having the slotted end 113 which is adapted to engage the lower surface of the locking nut 114, which is adjustably 110 mounted upon the stem 84 by means of 115 screw-threads, this cap being held in any 115 adjusted position by means of balls 115, 115 held in diametrically opposite vertical groove 116 by means of springs 117 disposed in pockets with the balls. The slotted 120 end 113 of the lever 112 embraces the stem 84, as shown in Fig. 1. The slotted end 118 of the lever 112 engages the head 119 of the spindle 120, the lower part of which is threaded and thus carries the needle valve 121. The spindle 120 may be adjusted as desired within the valve piece 121 and is held in its adjusted position by means of a set screw 122. A helical spring 123 encircles the spindle 120 and is disposed be- 125

tween the valve piece 121 and the top wall of the pocket 124 in which the spindle 120 operates. The lower end of the valve piece 121 is beveled to a point and engages the flaring end 125 of the oil passage 126 in the main casing. This passage extends downwardly and is closed at its lower end by means of the plug 127. The passage 20 extends to the right (Fig. 1) beyond the oil well formed by the sleeves 15 and 16 and on its end is provided with a threaded portion which communicates with the exterior. A plug 128 provided with a passageway 129 therethrough is inserted in the passage 20 so that it does not close or contract the passage 126. The end of the passage 20 is closed by means of the screw plug 129'. The arrangement just described is particularly desirable for cleaning purposes.

As before pointed out, the effective area of the primary nozzle is permanently adjusted by means of the adjusting member 25 and the tension of the spring 95 is also adjusted by means of the cup 91. These parts having been properly set to meet the existing conditions, the carbureter is ready for operation. The spring 61' which is associated with the float chamber is also properly adjusted. In starting, the lever 42 is moved so as to nearly close the central main air passageway through the carbureter, and it is clear that such operation will cause most of the suction to concentrate upon the nozzle opening 18. Depending upon the extent to which the main passageway is closed, the valve 82 may or may not respond. It is a matter of control and it is possible that the conditions may be met with in various ways. It is clear that choking the main air passageway in this way and thus concentrating the suction upon the fuel inlet, the mixture will become a rich one such as is required in starting. In the running of the engine, if it is desired to change the richness of the mixture, the bell-crank lever 104 may be actuated by the operator from his position and the tension of the spring 95 may in that way be adjusted, as has heretofore been described, to change the pressure upon the under side of the valve 82 and to thus change the degree of suction to which the valve is responsive. It is clear that by means of the lever 112 the opening of the valve 82 is accompanied by a corresponding opening of the supplemental fuel passage 126 and in this way the additional fuel for combustion is supplied. The primary objects of my invention are consistent with my aim to secure operation which is simple and construction which is inexpensive and practical.

What I claim is:

1. In a carbureter, the combination of a reservoir for supplying liquid fuel, a mix-

ing chamber, a main permanently open fuel inlet, a main air inlet, an auxiliary air valve, an auxiliary fuel inlet disposed in the path of air entering past said valve, means for normally closing said auxiliary fuel inlet, 70 and means for opening said fuel inlet by the action of said auxiliary air valve.

2. In a carbureter, the combination of a reservoir for supplying liquid fuel, a mixing chamber, a main fuel inlet, a main air inlet, an auxiliary air valve, an auxiliary fuel inlet, means for normally closing said auxiliary fuel inlet, and means for opening said fuel inlet by the action of said auxiliary air valve when said auxiliary air valve 80 has been opened a predetermined amount.

3. In a carbureter, the combination of a reservoir for supplying liquid fuel, a mixing chamber, a main permanently open fuel inlet, a main air inlet, an auxiliary air valve, said valve adapted to be unseated by the suction within said carbureter, an auxiliary fuel inlet disposed in the path of air entering past said valve, means for normally closing said auxiliary fuel inlet, and 90 means for automatically opening said fuel inlet when said auxiliary air valve is unseated.

4. In a carbureter, the combination of a reservoir for supplying liquid fuel, a mixing chamber, a main permanently open fuel inlet, a main air inlet, an auxiliary air valve, said valve adapted to be unseated by the suction within said carbureter, an auxiliary fuel inlet disposed in the path of air entering past said valve, a valve for closing said fuel inlet, and means for automatically opening said fuel inlet when said air valve is unseated.

5. In a carbureter, the combination of a reservoir for supplying liquid fuel, a mixing chamber, a main fuel inlet, a main air inlet, an auxiliary air valve, said valve adapted to be unseated by the suction within said carbureter, an auxiliary fuel inlet, a 110 valve for normally closing said auxiliary fuel inlet, and means for automatically opening said valve when said air valve is unseated and moved a predetermined amount.

6. In a carbureter, the combination of a reservoir for supplying liquid fuel, a mixing chamber, a main fuel inlet, a main air inlet, an auxiliary air valve, said valve adapted to be unseated by the suction within said carbureter, an auxiliary fuel inlet, a valve for closing said fuel inlet, means for automatically opening said fuel inlet when said air valve is unseated, and means for regulating the distance which said auxiliary 125 valve is required to move before said auxiliary fuel inlet is opened.

7. In a carbureter, the combination of a reservoir for supplying liquid fuel, a mixing chamber, a main permanently open 130

fuel inlet, a main air inlet, a normally seated auxiliary air valve, said valve adapted to be unseated by the suction within said carbureter, means for regulating the pressure tending to seat said auxiliary air valve, an auxiliary fuel inlet disposed in the path of air entering past said valve, means for normally closing said auxiliary fuel inlet, and means for opening said fuel inlet by the action of said auxiliary air valve.

8. In a carbureter, the combination of a reservoir for supplying liquid fuel, a mixing chamber, a main fuel inlet, a main air inlet, an auxiliary air valve, an auxiliary fuel inlet, passages for supplying liquid fuel to the main and auxiliary fuel inlets, a restricted opening in the passage supplying fuel to the auxiliary fuel inlet, and means for varying to any degree the flow of fuel through said auxiliary fuel inlet by the movement of the auxiliary air valve.

9. In a carbureter, the combination of a reservoir for supplying liquid fuel, a mixing chamber, a main fuel inlet, a main air inlet, an auxiliary air valve, an auxiliary fuel inlet, passages for supplying liquid fuel to the main and auxiliary fuel inlets, a removable plug in the passage supplying fuel to the auxiliary fuel inlet, said nozzle having a restricted opening therethrough, and means for varying to any degree the flow of fuel through said auxiliary fuel inlet by the movement of the auxiliary air valve.

10. In a carbureter, the combination of a reservoir for supplying liquid fuel, a mixing chamber, a main fuel inlet, a main air inlet, an auxiliary air valve, spring means for normally keeping said valve seated, means for regulating the tension of said spring means, an auxiliary fuel inlet, means for normally closing said auxiliary fuel inlet, and means for automatically opening said fuel inlet by less than the whole movement of the auxiliary air valve.

45 11. In a carbureter, the combination of a reservoir for supplying liquid fuel, a mixing chamber, a main fuel inlet, a main air inlet, an auxiliary air valve, an auxiliary fuel inlet disposed in the path of air entering past said valve, a tapered stem normally closing the auxiliary fuel inlet, a spring normally holding said stem seated in said inlet, and means for moving said stem from said inlet when the auxiliary air valve is unseated.

55 12. In a carbureter, the combination of a reservoir for supplying liquid fuel, a mixing chamber, a main fuel inlet, a main air inlet, an auxiliary air valve, an auxiliary fuel inlet, a tapered stem normally closing the auxiliary fuel inlet, a spring normally holding said stem seated in said inlet, and a lever, one end of which engages said stem, and the other end of which engages said

auxiliary air valve, said lever thereby adapted to unseat said stem when the auxiliary air valve is unseated.

13. In a carbureter, the combination of a reservoir for supplying liquid fuel, a mixing chamber, a main fuel inlet, a main air inlet, an auxiliary air valve, an auxiliary fuel inlet, a tapered stem normally closing the auxiliary fuel inlet, a spring normally holding said stem seated in said inlet, a head on said stem, a second stem for the auxiliary air valve, a head on said second stem, and a lever, one end of which engages the head of the first stem and the other end of which engages the head of the second stem, said lever thereby adapted to unseat the stem from the fuel inlet when the auxiliary air valve is unseated.

14. In a carbureter, the combination of a reservoir for supplying liquid fuel, a mixing chamber, a main fuel inlet, a main air inlet, an auxiliary air valve, an auxiliary fuel inlet, a tapered stem normally closing the auxiliary fuel inlet, a spring normally holding said stem seated in said inlet, an adjustable head on said stem, a second stem for the auxiliary air valve, a head on said second stem, and a lever, one end of which engages the head of the first stem, and the other end of which engages the head of the second stem, said lever thereby adapted to unseat the stem from the fuel inlet when the auxiliary air valve is unseated.

15. In a carbureter, the combination of a reservoir for supplying liquid fuel, a mixing chamber, a main fuel inlet, a main air inlet, an auxiliary air valve, an auxiliary fuel inlet, a tapered stem normally closing the auxiliary fuel inlet, a spring normally holding said stem seated in said inlet, a head on said stem, a second stem for said auxiliary air valve, an adjustable head on said second stem, means for locking said head in its adjusted position, and a lever, one end of which engages the head of said first stem, and the other end of which engages the head of the said second stem, said lever thereby adapted to unseat the first stem from said fuel inlet when the auxiliary air valve is unseated.

16. In a carbureter, the combination of a reservoir for supplying liquid fuel, a mixing chamber, a main fuel inlet, a main air inlet, an auxiliary air valve, an auxiliary fuel inlet, a tapered stem normally closing the auxiliary fuel inlet, a spring normally holding said stem seated in said inlet, an adjustable head on said stem, a second stem for said auxiliary air valve, an adjustable head on said second stem, means for locking said second head in position, and a lever, one end of which engages the head of said first stem, and the other end of which engages the head of said second stem, said lever thereby

adapted to unseat the first stem from said fuel inlet when the auxiliary air valve is unseated.

17. In a carbureter, a casing having an outlet, a throttle in said outlet, a carbureting chamber on one side of said throttle, a main air inlet for said chamber, an auxiliary air inlet for said chamber, a suction operated valve for said auxiliary air inlet, a main fuel nozzle disposed in said main air inlet, an auxiliary fuel nozzle disposed in the path of air entering said auxiliary air inlet, and means for controlling the outlet of said auxiliary fuel nozzle, said controlling means operating automatically in response to said suction during the movement of said valve.
- 10 18. In a carbureter, a casing having an outlet, a throttle in said outlet, a carbureting chamber on one side of said throttle, a main air inlet for said chamber, an auxiliary air inlet for said chamber, a suction operated valve for said auxiliary air inlet, a main fuel nozzle disposed in said main air inlet, an auxiliary fuel nozzle disposed in the path of air entering said auxiliary air inlet, and means for controlling the outlet of said auxiliary fuel nozzle, said controlling means operating automatically in response to said suction during the movement of said valve.
- 15 19. In a carbureter, a carbureting chamber, a main air inlet therefor, an auxiliary air inlet therefor, a valve for said auxiliary air inlet, a main fuel nozzle disposed in said main air inlet, an auxiliary fuel nozzle disposed in the path of air entering said auxiliary air inlet, and means for controlling the outlet of said auxiliary fuel nozzle, said controlling means being operated by the movement of said valve.

- 20 20. In a carbureter, a carbureting chamber, a main air inlet therefor, an auxiliary air inlet therefor, a valve for said auxiliary air inlet, a main fuel nozzle disposed in said main air inlet, an auxiliary fuel nozzle disposed in the path of air entering said auxiliary air inlet, and means for controlling the outlet of said auxiliary fuel nozzle, said controlling means being operated by the movement of said valve.
- 25 21. In a carbureter, a carbureting chamber, a main air inlet therefor, an auxiliary air inlet therefor, a suction operated valve for said auxiliary air inlet, a main fuel nozzle disposed in said main air inlet, an auxiliary fuel nozzle having its outlet at a considerably higher level than that of the main fuel nozzle, and a valve controlling the outlet from said auxiliary fuel nozzle, the fuel valve being arranged to operate during the movement of the air valve.
- 30 22. In a carbureter, a carbureting chamber, a main air inlet therefor, an auxiliary air inlet therefor, a suction operated valve

for said auxiliary air inlet, a main fuel nozzle disposed in said main air inlet, an auxiliary fuel nozzle disposed in the path of air entering said auxiliary air inlet, and means for controlling the outlet of said auxiliary fuel nozzle, said controlling means being operated by the movement of said valve.

23. In a carbureter, a carbureting chamber, a main air inlet therefor, an auxiliary air inlet therefor, a suction operated valve in said auxiliary air inlet, a normally open valve in said main air inlet, a main fuel nozzle disposed in said main air inlet, independent means for operating said main air inlet valve to temporarily restrict the main air inlet, and separate manually operated lever mechanism for momentarily holding said auxiliary air valve closed.

24. In a carbureter, a carbureting chamber, a main air inlet therefor, an auxiliary air inlet therefor, a suction operated valve in said auxiliary air inlet, a normally open valve in said main air inlet, a main fuel nozzle disposed in said main air inlet, independent means for operating said main air inlet valve to temporarily restrict the main air inlet, and manually operated lever mechanism for temporarily increasing the seating tension on said suction operated valve.

25. In combination, a double carbureter, each element comprising an air inlet and a fuel inlet, each fuel inlet being disposed in the pathway of the air entering its respective air inlet so as to be directly subject to the aspirating effect of the air entering its respective air inlet but not so subject to the air entering through the other air inlet, the air inlet of one carbureting element being normally open, a suction controlled valve controlling the air inlet of the other carbureting element, a valve controlling the fuel inlet of said other carbureting element, and means for mechanically connecting said valves.

26. In combination, a double carbureter, each element comprising an air inlet and a fuel inlet, each fuel inlet being disposed in the pathway of the air entering its respective air inlet so as to be directly subject to the aspirating effect of the air entering its respective air inlet but not so subject to the air entering through the other air inlet, the air inlet of one carbureting element being normally open, a suction controlled valve controlling the air inlet of the other carbureting element, a valve controlling the fuel inlet of said other carbureting element, and means for mechanically connecting said valves, the fuel inlet of one of said carbureting elements being disposed at a higher plane relative to a maintained fuel level than the fuel nozzle of the other carbureting element.

27. In a carbureter, a casing having an

outlet, a throttle in said outlet, a constant level supply chamber for supplying liquid fuel, a carbureting chamber on one side of said throttle, a main air inlet for said chamber, an auxiliary air inlet for said chamber, a suction operated valve for said auxiliary air inlet, a main fuel nozzle disposed in said main air inlet, an auxiliary fuel nozzle having its outlet at a considerably higher level than that of the main fuel nozzle and disposed in the path of air entering said auxiliary air inlet, and a valve controlling the outlet from said auxiliary fuel nozzle,

the fuel valve being arranged to operate during the movement of the air valve, each fuel nozzle being subject to the aspirating effect of the air entering its respective air inlet, but not so subject to the aspirating effect of the air entering the other air inlet.

In witness whereof, I hereunto subscribe 20 my name this 28th day of February, A. D. 1914.

JOHN S. GOLDBERG.
